UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

CURTAIN-ROD.

1,315,704.

Specification of Letters Patent. Patented Sept. 9, 1919.

Application filed October 28, 1918. Serial No. 259,965.

To all whom it may concern:

Be it known that GUSTAF A. CARLSON, a citizen of Sweden, who has taken out first papers for citizenship in the United States, 5 residing at Chicago, in the county of Cook and State of Illinois, has invented a new and useful Improvement in Curtain-Rods, of which the following is a specification.

This invention relates particularly to 10 flexible curtain-rods, such as are commonly employed for sash-curtains.

Curtain-rods of the type here referred to comprise close-wound spring wire coils. Such flexible rods are usually made of 15 closely coiled piano spring wire. At the present time, such wire is quite expensive and difficult to obtain; and, moreover, when a curtain-rod is constructed wholly of coiled wire, it is likely to be more flexible than is 20 desirable.

The primary object of the present invention is to provide a construction which enables the desirable features of the close-wound spring wire coil to be retained, and 25 which enables the objectionable features to be obviated.

This purpose is accomplished by means of the invention illustrated in the accompanying drawing, in which—

30 Figure 1 represents a broken plan view of a window-frame, or sash, equipped with a curtain-rod (shown brokenly) constructed in accordance with my invention; Fig. 2, a broken elevational view of the same; Fig. 3, 35 a plan view of one of the close-wound wire coils employed in the construction; Fig. 4, a perspective view of a sleeve employed; Fig. 5, a fragmentary view of a heavy wire or intermediate rod-section employed in the 40 construction; Fig. 6, a broken sectional view illustrating the manner in which the ends of the intermediate rod-section are joined to the wire coils; Fig. 7, a view of a slightly modified form of intermediate rod-section; 45 and Fig. 8, a view of a further slight modification.

In the construction illustrated, A represents a window-frame, or sash; B, a pair of brackets applied to said frame; and C, an 50 improved curtain-rod mounted in the brackets B.

The brackets B may be of any suitable form. The brackets are preferably provided

with sockets 1 adapted to engage grippers with which the extremities of the curtain- 55 rod preferably are equipped.

The curtain-rod preferably comprises an intermediate rod-section, or piece of comparatively stiff wire 2; a pair of resilient rod-sections, or wire coils, 3; sleeves 4 adapted to serve as clamping connections between the inner ends of the coils 3 and the extremities of the intermediate rod-section 2, which are extended into the coils; and grippers 5 which are applied to the outer ends of the 65 coils 3 and introduced into the sockets 1 of the brackets B.

It may be stated here that the grippers 5 are adapted to hold the curtain-rod C under tension between the brackets B in the 70 manner described in my co-pending application No. 259,966, filed of even date herewith. The intermediate-rod-section 2 has its end-portions provided with slight off-sets, or crimps, 6. The rod-section 2 is of the proper 75 diameter to fit snugly in the end-portion of the coil 3. When the end-portion of the rod 2 is introduced into the end-portion of the coil in the manner shown in Fig. 6, it produces a curvature of the coil; and when 80 the sleeve 4 is slipped into position to embrace the end-portion of the coil and the inserted portion of the rod-section 2, the effect is to cause a wedging action within the sleeve. In other words, the sleeve 4, which 85 may be a split sleeve formed from sheet-metal, acts as a clamping sleeve, which firmly secures the end-portion of the rod-section 2 to the coil-spring into which it is introduced. The gripping action is such as 90 to prevent disengagement when the curtain-rod is placed under tension, as occurs when the grippers 5 are introduced into the brackets B.

If it be desired to separate the rod-section 95 2 from the coil-spring, this may be effected by tapping the sleeve endwise until it ceases to encircle the portion of the coil which contains the crimped or off-set portion of the wire, after which the wire may be readily 100 withdrawn from the coil.

It will be understood that the construction described provides for adjustment of the length of the curtain-rod when the curtain-rod is first installed, enabling the curtain-rod to be placed under just the desired 105

tension. In case the coils are weakened by use and it becomes necessary to shorten the curtain-rod, this may be accomplished by re-adjustment of the coils upon the ends of 5 the intermediate rod-section, the sleeve being first removed and then forced again to the clamping position.

The construction described possesses the advantage that it requires the use of only 10 comparatively small sections of piano steel wire for forming the coils. It also possesses the advantage of obviating undue flexibility of the curtain-rod while still retaining the desirable feature of tension upon the 15 curtain-rod. The intermediate section 2 may be of strong stiff wire. In practice, the wire coils need not be more than a few inches in length, even in a curtain-rod which is upward of thirty inches in length. In such a 20 curtain-rod, for example, it will suffice to employ coils of about four inches in length, or even smaller.

In Fig. 7, 2^a indicates an intermediate rod-section having a slightly different offset 25 set 6^a at the end-portion adapted to enter the coil-spring.

In Fig. 8, 2^b represents an intermediate rod-section having a slightly enlarged portion 30 6^b, formed by slightly flattening the wire. In this case, the wire must be slightly smaller than the coil spring which it enters, and the embracing sleeve must be sufficiently small in diameter to force the coils closely against the walls of the enlargement. In 35 each case, the object is to produce such a deformation in the portion of the wire which is introduced into the coil as to cause a clamping or gripping action when the sleeve is caused to embrace the coil and the inserted portion of the wire-rod.

The foregoing detailed description has been given for clearness of understanding only, and no unnecessary limitations should be understood therefrom, but the appended

claims should be construed as broadly as 45 permissible in view of the prior art.

What I regard as new, and desire to secure by Letters Patent, is:

1. A curtain-rod comprising a pair of coiled wire sections equipped with bracket- 50 attaching means, an intermediate relatively stiff-rod-section, and means securing the inner ends of said coiled wire sections to said intermediate section.

2. A curtain-rod comprising a pair of 55 coiled wire sections, an intermediate relatively stiff rod-section having its end-portions extending into said first-named sections, and clamping means embracing the joints between said intermediate section and the 60 coiled wire sections and securing said parts together.

3. A curtain-rod comprising a coiled wire section, a wire-rod section extending thereinto, and a sleeve clamping said sections together. 65

4. A curtain-rod comprising a coiled wire section, a wire-rod section having an end-portion extending into said coiled wire section and provided with a deformation, and 70 a sleeve embracing said members at the joint and serving to secure said members together.

5. A curtain-rod comprising a coiled wire section, a wire-rod section having an end-portion extending thereinto and provided 75 with a bend, and a sleeve embracing said sections at the joint and securing them together.

6. A curtain-rod comprising a pair of coiled wire end-sections, an intermediate wire 80 rod section having portions extending into said coiled wire sections and provided therein with deformations, clamping sleeves embracing said sections at the joints and securing said sections together, and bracket- 85 attaching means associated with the outer end-portions of said coiled wire sections.

GUSTAF A. CARLSON.
